Inventor:
Charles W. Wadsworth

UNITED STATES PATENT OFFICE.

CHARLES W. WADSWORTH, OF BROOKLYN, NEW YORK.

HAND-RAIL FOR BATH-TUBS.

1,147,348.

Specification of Letters Patent. Patented July 20, 1915.

Application filed December 22, 1914. Serial No. 878,472.

To all whom it may concern:

Be it known that I, CHARLES W. WADSWORTH, a citizen of the United States, residing at Brooklyn, in the county of Kings, State of New York, have invented a new and useful Hand-Rail for Bath-Tubs, of which the following is a specification.

Accidents resulting in serious injuries to bathers by slipping and falling in bath tubs, 10 are very frequent since the porcelain lined and other smooth surfaced tubs have come into such general use. In case one slips there is but little chance to avoid a fall, as there is no available support except to grasp 15 the roll or rim of the tub, which is usually smooth surfaced and very difficult to hold.

The object of my invention is to provide a safety hand rail that can be securely attached to the tub in a convenient position to 20 be grasped for steadying and supporting a person when getting into or when rising and getting out of the tub.

My device is simple of construction, inexpensive, durable, easily attached to or removed from the tub.

The mechanism is illustrated in the accompanying drawing.

Similar letters refer to similar parts throughout the several views.

Figure 1 is a perspective view of the complete hand rail and a section of a bath tub, showing attachment to the roll. Fig. 2 is a perspective view of one of the pair of identical metal standards. Fig. 3 is a perspective view of the crossbar with nut fitting.

Detailing the drawings: Fig. 2. A standard, one piece metal, (a) head fitted with eye, sleeve, notch, or other device for rigid and secure fastening of crossbar by use of 40 screw, nut, pin, bolt or other device; (b) vertical part, upright divided in lower half and spread; (c) footing and angle, footings turned on the parts of (b) as divided, to rest on and conform to the roll of the tub, 45 extending from the beginning of the flare on the inner side of the roll outward over the roll, and turned up under the outer edge, the footings to be turned at an angle to secure the upright (b) in a vertical position. 50 The vertical part (b) and footings (c) may

be single, but prefer to apply divided, as shown in drawings.

Fig. 3. Crossbar with nut fitting, (d) bar, wood, metal or other substance, used alone or in combination; (e) nut fitting to correspond with thread on (d) or any other type of fitting for securing rigid attachment of (d) and (a).

My device is designed for use on any size or make of bath tub having a roll with free 60 edge finish, and the length of crossbar, the height of standards and the shape of their footings will be varied to fit the tub on which used. The parts should be so proportioned that when mounted on the tub the 65 hand rail will be across and at a height above the tub to be conveniently reached by a person seated in the tub, and the whole to be of strength and rigidity sufficient to sustain an approximate weight of 300 70 pounds or stand a pull of like amount.

The attachment to the bath tub is made by resting the footings of the standards on the roll on the opposite sides of the tub, the footings, fitting over and engaging under 75 the free edge of the roll, securing the standards in an upright position. The crossbar is made shorter than the free space between the heads of the standards, to which its ends are attached by drawing in the heads 80 of the standards on a smart tension, this leverage resulting in a rigid grip of the footings on the roll. The under surface of the footings may be lined with rubber or other substance for the protection of the 85 roll of the tub.

This device may be attached to the roll on the sides of the tub at any place desired. When attached near the foot it is in a position to be conveniently grasped by the 90 bather and does not interfere with the free use of the tub.

I claim:

1. The combination, with a bath tub, of a pair of metal standards located on the roll 95 on the opposite sides of the tub, having their footings fitted to the roll and engaged under its free edge, their bodies extended vertically above the roll; a bar having its ends securely attached by proper fittings to the 100

heads of the standards, the bar shorter than the free space between the heads of the standards, with which the connection is effected by drawing in the heads on a smart tension, all substantially as set forth.

2. The combination, with a bath tub, of a crossbar having its ends securely attached by proper fittings, to a pair of metal stand-

ards having their footings resting on, fitted to and turned up under the outer edge of 10 the roll on the opposite sides of the tub, all substantially as set forth.

CHARLES W. WADSWORTH.
